UNITED STATES PATENT OFFICE.

SHEDRICK WHITTER, OF SAFETY HARBOR, FLORIDA.

ELECTRICAL-CONDUCTOR SUPPORT.

1,275,116.

Specification of Letters Patent.

Patented Aug. 6, 1918.

Application filed November 12, 1917. Serial No. 201,503.

To all whom it may concern:

Be it known that I, SHEDRICK WHITTER, a citizen of the United States, residing at Safety Harbor, in the county of Pinellas and 5 State of Florida, have invented certain new and useful Improvements in Electrical-Conductor Supports, of which the following is a specification.

This invention relates to supports and the 10 invention has more particular reference to an improved electrical conductor support for telegraph poles.

The invention has for its principal object to provide an electrical conductor support 15 adapted for arrangement on telegraph poles and the like, whereby the usual insulator can be arranged thereon and a plurality of electrical conductors then engaged with the same and properly supported.

20 Another and equally important object of the invention is to provide a support capable of pivotal movement in order that the conductors may be easily and quickly engaged therewith and then stretched.

25 Another object of the invention is to provide a support of the character mentioned which is of simple construction and one which will not be affected by its constant subjection to the elements.

30 Other objects will be in part obvious and in part pointed out hereinafter.

The foregoing together with additional advantageous details and arrangement of parts of the preferred embodiment of my invention will be clear from the specific description hereinafter contained, when read in connection with the accompanying drawings forming part thereof, wherein said embodiment of the invention is illustrated for 40 the purpose of facilitating a full understanding of the present improvements.

In the drawings:—

Figure 1 is a front elevation of the improved conductor support,

45 Fig. 2 is a top plan of the same, and,

Fig. 3 is a fragmentary detail in perspective of one of the conductor supports.

Having more particular reference to the drawings and in connection with which like 50 reference characters will designate corresponding parts in the several views, 1 represents the base strip of the bracket, the same being substantially U-shaped and provided with a tapered deflector 2 which, as will be 55 noted, is arranged upon the upper portion thereof and obviously serves to prevent the

lodging of snow or ice upon the top of the telegraph pole T to which the improved support is applied. Laterally extending arms 3 are formed integral with the extremities 60 of the base strip 1 and as will be noted, vary in length and have the outer ends thereof rolled to provide efficient bearings 4, the purpose of which will be presently apparent. Suitable openings are formed in the 65 extremities of the U-shaped base strip 1 and permit the passing of bolts 5 or similar fastening devices therethrough, whereby the said base will be effectually secured to the pole.

Secured to or formed integral with the upper portions of the base strip 1 are oppositely disposed bracketed arms 6 having reduced portions 7 formed thereon.

Supports generally indicated by the numerals 8 and 9 are provided and have downwardly extending bearing pintles 10 formed thereon, which bearing pintles are received in the rolled bearing portions 4 formed upon the extremities of the laterally extending arms 3. Offset arms 11 extend from the various supports 8 and 9 and are provided with catches 12 adapted to be engaged over the adjacent marginal edges of the extremities of the base strip 1. Insulator receiving fingers 13 are formed integral or otherwise arranged on the supports 8 and 9 and are adapted to detachably receive insulators I thereover, which insulators have engagement with the electrical 90 conductors E to be supported. As will be noted, the supports 8 are provided with a less number of insulator receiving fingers 13 and also, that the same are of less length than the remaining supports 9.

95 Due to the lengths of the laterally extending arms 3 the pivotal supports 8 and 9 will be arranged in relatively stepped relation as clearly shown in the Fig. 1, thus, causing the weight to be evenly applied to the telegraph pole T.

Another support 14 is provided and carries depending tubular brackets or sleeves 15 receivable over the reduced portions of the bracket arms 6. A plurality of insulator 105 receiving fingers 16 are arranged on the said support and as will be understood, receive insulators I thereon. In this connection, it is to be understood that the bracket 14 is detachably engaged with the reduced portions 110 of the bracket arms 6, thus, allowing the same to be removed as the occasion arises.

Attention is also directed to the fact that the supports 8 and 9 are detachably engaged with the laterally extending arms 3, thus, permitting the same to be placed or removed 5 as it becomes necessary.

In using the improved support, the base strip is of course secured over the upper end of the telegraph pole T by means of bolts or other suitable fastening devices 5, where- 10 upon the desired number of supports 8 and 9 are engaged with the arms 3. Insulators I are then placed over the fingers 13 and the electrical conductors E properly engaged therewith. Subsequent to the engagement 15 of the electrical conductors E with the insulators, the supports 8 and 9 are then swung in directions to cause engagement of the catches 12 carried upon the offset arms 11 with the adjacent marginal edges of the ex- 20 tremities of the base strip 1. In this way, the electrical conductors will be held taut at all times and also, may be engaged with the supports much more rapidly than in the constructions heretofore prevalent in the art.

Copies of this patent may be obtained for five cents each, by addressing the "Commissioner of Patents, Washington, D. C."

Manifestly, the construction shown is capable of considerable modification and such modification as is within the scope of my claims, I consider within the spirit of my invention.

I claim:—

1. A device of the character described including a substantially U-shaped base, laterally extending arms varying in length arranged on the extremities of said base, and pivotal supporting means detachably mount- 35 ed on said arms.

2. A device of the character described including a substantially U-shaped base, laterally extending arms varying in lengths ar- 40 ranged on the extremities of said base, piv- otal supports detachably mounted on said arms, and means engaged with the supports and engageable with said base for stretching electrical conductors thereon.

In testimony whereof, I affix my signature 45 hereto.

SHEDRICK WHITTER.
